UNITED STATES PATENT OFFICE.

TIMOTHY J. CROWLEY, OF LONG ISLAND CITY, NEW YORK.

KNEE-PROTECTOR.

1,117,168.

Specification of Letters Patent. Patented Nov. 17, 1914.

Application filed April 21, 1914. Serial No. 833,488.

To all whom it may concern:

Be it known that I, TIMOTHY J. CROWLEY, a citizen of the United States, residing at Long Island City, in the county of Queens 5 and State of New York, have invented certain new and useful Improvements in Knee-Protectors, of which the following is a full, clear, and exact specification.

This invention relates to knee protectors, 10 and has for its object to provide a device of this kind which will not only permit the wearer to kneel on the ground without danger of taking cold or contracting rheumatism or some kindred disease, but which will 15 afford comfort to the wearer in this more or less strained position which must necessarily be assumed in weeding gardens, scrubbing floors, laying carpets, etc.

Another object is to provide more effective 20 means for holding the protector in place when in use, thereby relieving the limbs of the wearer from undue binding or strain.

Other objects will appear as the description proceeds.

25 The invention will be first hereinafter described in connection with the accompanying drawings, which constitute a part of this specification, and then more specifically defined in the claims at the end of the description.

30 In the accompanying drawings, wherein similar reference characters are used to designate corresponding parts throughout the several views:—Figure 1 is a side view of 35 the knee protector, partly in section and applied as in use. Fig. 2 is a front elevation of the knee protector and Fig. 3 is a rear elevation of the same.

Referring more particularly to the drawings, 40 1 designates the body portion of the protector which contains a pneumatic chamber 2 controlled by a valve or tube 3. This body portion of the protector is made wide enough to extend well across the knee and 45 long enough to extend some distance both below and above the knee so as to afford ample protection. From the lateral edges of the body portion members 4 extend rearwardly to cover the sides of the wearer's 50 limb practically the full length of the body portion. These lateral members have projecting portions 5 near the upper and lower ends thereof, which portions extend around to the back of the limb and are adjustably 55 connected together in pairs by lacings 6, as clearly shown in Figs. 1 and 3. It will be

noted that one pair of these laced portions 5 is arranged well above the knee and the other pair well below the same, thus providing means for attaching the protector to the 60 limb which is not only adjustable to fit different sizes of persons but which is also of such form as not to bind or cause discomfort in use, said laced portions being wide and therefore incapable of exerting a cutting pressure 65 upon the limb such as would be experienced if a strap or single cord were used. To further promote the comfort of the wearer and retain the protector in proper position against working up on the limb in use, I 70 provide a foot strap 7 attached to the lower end of the side members 5 and adapted to be passed under the instep of the shoe, as illustrated in Fig. 1. This shoe strap may be adjustably secured in any suitable manner, as by the buckle 8 shown. Its adjustment allows for fitting the protector to persons with different lengths of limbs, and positively prevents the protector from shifting 75 upward on the limb so as to expose the 80 knee.

The pneumatic chamber in the body portion of the protector provides a most comfortable cushion for the knee to rest upon while performing the various kinds of work 85 requiring a kneeling posture. In practice, the pneumatic chamber is inflated before the protector is attached to the limb. It is then a simple matter to adjust the laced portions 5 and the foot strap 7 to suit the 90 wearer without binding or causing any other form of discomfort.

Having thus described my invention, what I claim as new and desire to secure by Letters Patent of the United States is:—

1. In a knee protector, the combination with a flexible pneumatic body portion to cover the front of the knee and extend well above and below the same, of lateral members extending along the full length of the 100 body portion and rearwardly therefrom for covering the sides of the knee and also the sides of the limb above and below the same, adjustable means attached to said lateral members to be secured at the back of the 105 limb both above and below the knee, and adjustable means for connecting the protector to the foot of the wearer.

2. In a knee protector, the combination with a body portion to cover the front of 110 the knee, of lateral members attached to the edges of the body portion and extending

- substantially the full length of the protector, wide rearwardly extending portions at opposite end portions of the lateral members, lacings for adjustably connecting said rearwardly extending portions together in pairs at the back of the limb well above and below the knee, and adjustable means for connecting the protector to the foot of the wearer.
- 10 3. In a knee protector, the combination with a body portion to cover the front of the knee, of lateral members attached to the edges of the body portion to cover the sides

of the knee, means for adjustably connecting said lateral members at the back of the knee, 15 and flexible adjustable means attached to said lateral members and passed below the instep of the foot of the wearer for the purposes specified.

In testimony whereof I have signed my 20 name to this specification in the presence of two attesting witnesses.

TIMOTHY J. CROWLEY.
